ELEVATOR DOOR GUIDE

Ralph L. Henry, Detroit, Mich., assignor to Hen-
rite Products Corporation, Ironton, Ohio, a
corporation of Ohio

Application February 11, 1931, Serial No. 515,034

4 Claims. (Cl. 16—93)

This invention relates, generally, to elevators; and the invention has reference, more particularly, to a novel form of guide for use on elevator doors such as hatchway doors or car doors.

5 As an elevator car travels up and down a hatchway, its movement creates a region of increased pressure ahead of the car and a region of reduced pressure behind the car. These variations in pressure, created by the movement of the car, 10 cause elevator doors such as hatchway doors and car doors to rattle or vibrate, which rattling is very disturbing and objectionable especially in buildings having high speed elevators. Elevator doors as at present constructed, merely employ 15 metal guide shoes which ride in guide grooves provided in the metal threshold plates of floor landings and elevator cars. The metal to metal contact of the guide shoes with the sides of the guide grooves, and especially the inherent looseness of the guide shoes within the guide grooves of the threshold plates tends to greatly increase the rattling noises.

The principal object of the present invention 25 is to provide a novel elevator door guide which is adapted to be readily applied to elevator doors, such as car and hatchway doors, and which acts to eliminate rattle or other noise of the doors normally caused by movement of the car within the hatchway.

30 Another object of the present invention lies in the provision of a novel elevator door guide which is non-metallic and is self-lubricating, the same being so constructed and arranged as to automatically take up any looseness or wear and to thereby prevent any looseness between the guide 35 and the guide groove within which it moves.

Still another object of the present invention 40 is to provide a novel elevator door guide comprising two pivotally mounted shoes which are adapted to be attached to an elevator door by the screws now used for holding the common metal door guide to the elevator door, the said door having spring means interposed therebetween for urging them into sliding engagement 45 with the sides of the threshold plate guide groove.

Other objects of this invention not at this time more particularly enumerated will be clearly understood from the following detailed description of the same.

50 The invention is clearly illustrated in the accompanying drawings, in which:—

Fig. 1 is a schematic representation of an elevator in a hatchway with parts broken away and shows elevator doors equipped with the novel 55 guide shoes of this invention.

Fig. 2 is an enlarged fragmentary view of the bottom portion of an elevator door and illustrates the novel guide shoes of this invention attached thereto.

Fig. 3 is an enlarged fragmentary view of a 5 portion of the car threshold plate structure shown in Fig. 1.

Fig. 4 is a sectional view taken substantially along line 4—4 of Fig. 3 looking in the direction of the arrows.

Fig. 5 is a perspective view of a slightly modified form of guide.

Fig. 6 is a view similar to Fig. 4 but illustrates the use of the modified construction shown in Fig. 5; 10

Fig. 7 is an enlarged sectional view taken substantially along line 7—7 of Fig. 6 showing also the bottom portion of the door; and

Fig. 8 is a perspective view of a somewhat modified form of the invention. 15

Similar characters of reference are employed in all of the above described views to indicate corresponding parts.

Referring now to Figs. 1 and 2 of the said drawings, the reference numeral 1 designates an elevator car which is movable within the hatchway 2. The doors 3 and 3' of the car 1 and hatchway 2 are illustrated as equipped with the novel guides of this invention, which guides are designated as a whole by the reference numeral 5. The guides 30 5 are secured to the bottoms of the doors 3 and 3' and project into suitable guide grooves 4 provided in the threshold plate or sill of the elevator car and in the threshold plate or sill of the hatchway landings. In Fig. 3, the threshold plate 6 is 35 illustrated as of the self-cleaning type and has guide bars 7 which are engaged by the door guides 5. As especially shown in Figs. 2 and 4, each of the door guides 5 comprises two similar and oppositely disposed swivel guide shoes 8 which 40 are pivotally mounted on vertical screws 9 threaded into the bottoms of the doors 3 and 3'. Screws 9 may be the same screws ordinarily used to hold a metal guide plate to an elevator door and may be inserted into the same holes provided 45 in the door bottom for holding the metal guide plate.

Guide shoes 8 are preferably made of molded material having self-lubricating properties. It has been found in practice that a molded mate- 50 rial consisting of asbestos, graphite and a condensation product, such as bakelite, serves very well for this purpose. The asbestos ingredient gives the desired body to the composition. The graphite ingredient serves to give the composition 55

the desired self-lubricating qualities and the condensation product serves as a binder.

A composition consisting of the following percentages by weight of these respective ingredients 5 has been found to be very satisfactory in practice.

	Percent
Asbestos	60
Graphite	20
10 Condensation product ("Bakelite")	20

A simple method of forming the guide shoe 8 is to prepare an intimate mix consisting of the above proportions of the ingredients in finely divided or powdered form, and then to place this mix in a mold of the proper shape and to either cold or preferably hot mold the mix with the application of suitable pressure. The guide shoe thus produced is found to be very rigid and strong and possesses the desired self-lubricating qualities for the use intended. The presence of the uniformly dispersed graphite throughout the body of the guide shoe serves, in conjunction with the other ingredients, to cause the shoe to have an extremely low coefficient of friction, so that the same will slide readily and easily within the guide groove of a threshold plate and with the exertion of but a minimum of tractive effort.

It is desired to point out that in practice it has been found that the percentages of the several ingredients making up the composition of the guide shoes may be varied within reasonable limits nor is it essential that the specific ingredients listed alone shall be used. For example, instead of using 60% asbestos in the above recited composition, it has been found that the percentage of asbestos may be reduced to 30% and 30% feldspar added in lieu of the remaining portion of asbestos.

Each of the guide shoes 8 has a prismatic body portion 10 of rectangular cross-section. The guide shoe is formed with a thickened end or head portion which is substantially twice the thickness of its body portion 10. This head portion is provided with a vertical, circular aperture 12 for receiving a screw 9. The guide shoe 8 is of sufficient height to enable the same to project into a guide groove 4 for the greater portion of the depth of this groove.

The body portions 10 of each pair of guide shoes forming a door guide are arranged in opposition to each other and have spring means interposed therebetween for urging these body portions outwardly into engagement with the sides or guide bars 7 of the elevator threshold plate guide groove 4. This spring means is illustrated in Figs. 2 and 4 as consisting of a pair of helical, conical springs 13. One of these springs 13 is illustrated as set within a circular depression 14 provided in one of the body portions 10. The frictional engagement of the wall of the circular depression 14 upon the spring 13 serves to retain this spring in proper position within the depression. The other of the springs 13 is illustrated as positioned within the depression 14 provided in the body portion 10 of the cooperating guide shoe 8. The compressive force of the springs 13 act to urge the guide shoes outwardly, as especially shown in Fig. 4, so that these guide shoes snugly engage the sides of the threshold plate guide groove 4 and thereby serve to firmly hold the bottom of the door, so that the same will not rattle or move transversely with respect to the guide groove 4.

Owing to the action of the springs 13 in tending

to move the guide shoes outwardly and away from one another, these shoes automatically adjust themselves to any width of guide grooves 4 and always engage the sides of the guide groove, thereby preventing rattling or vibration of the door. Owing to the low coefficient of friction of the guide shoes 8, these shoes slide along within the guide groove 4 in use without appreciable friction and with the application of a minimum of tractive effort upon the door. Any wear taking place at the sides of the guide groove 4 or on the guide shoes 8, is automatically compensated for by the expansive action of springs 13 which immediately act to take up this wear as it forms, so that the bottom of the door is therefore always firmly positioned with respect to the guide groove 4 and is not allowed to rattle.

It will be apparent that the guide shoes may have various shapes other than that shown in Figs. 1 to 4 of the drawings, and that any suitable expansive means may be used in lieu of springs 13 for urging the guide shoes outwardly into engagement with the sides of the guide grooves 4. Thus, in Figs. 5 to 7 a slightly modified form of guide shoe 8' is shown. The head portion of each 25 of the guide shoes 8' has the lower half thereof cut away and its body portion 10' is formed with a lower end projection 16 which is of the same shape as the cut out portion of the guide shoe head. Projection 16 of one guide shoe is adapted 30 to project into the cut away part of the head of the cooperating or opposed guide shoe 8'. Thus, the lower end projection 16 of each guide shoe underlies the head portion of its opposed and co-operating guide shoe as especially shown in Fig. 7. 35 The head portions of these guide shoes are provided with vertical circular apertures 12' for receiving the screws 9. The offset lower end projections 16 are provided with vertical apertures 18 which have the form of transverse slots to 40 permit transverse movement of the end projection with respect to the screws 9.

As especially shown in Fig. 7, the screws 9 are adapted to extend through apertures 18 and 12' and into the bottom of the door 3. Leaf springs 45 19 are illustrated as employed for urging the body portions 10' of the guide shoes away from one another and toward the sides of the guide groove 4. It will be apparent that the coil springs of Fig. 4 may be used in lieu of the leaf springs 19, 50 if desired, or an entirely different material such as a block of rubber may be employed for urging these guide shoes outwardly. It will be noted that the use of the lower end projections 16, in effect, increases the effective area of contact between the guide shoes and the sides of the guide groove 4.

In use, it has been found that the novel door guides have an extremely long life and positively prevent any noise of the car or hatchway doors. 60 The said door guides being of non-metallic material also eliminate wear of the threshold plate guides. It will be apparent that the novel door guide of this invention may be used for guiding any type of sliding door, such as sliding fire doors 65 and the like, and will act to positively prevent any rattling or other vibrational noise of the door, and it is therefore not intended to limit the invention to use on elevator doors per se.

Preferably the screw apertures 12 and 12' in 70 the guide shoes 8 are of sufficient diameter so that the screws 9 may have a slightly loose fit within these apertures 12 and 12' and will enable the head end portions of the guide shoes to move transversely slightly to thereby increase the ex- 75

tent of engagement between the guide shoes and the sides of the guide grooves 4 under the action of springs 13 or 19. In some instances as where the guide grooves 4 are of appreciably greater 5 width than the width of the guide shoes themselves, the apertures 12 may be transversely enlarged slightly in somewhat the same manner as apertures 18 are enlarged. In this way the guide 10 shoes will be expanded by the springs 13 and 19 so as to engage the sides of the guide grooves 15 along a considerable length of the guide shoes, regardless of the width of the guide groove.

It is desirable to point out that the expandible 20 feature of the guide of the present invention is considered very important because it is this feature which causes the same to always fit the guide groove, regardless of wear of either the guide or 25 guide groove. It is apparent that this expandible feature may be obtained in ways other than those illustrated in Figs. 1 to 7 of the drawings. Thus, in Fig. 8 a modified form of expandible 30 guide is shown. In this form of the invention, the guide shoe 21 has apertures 22 in its ends for attaching the same to the elevator door. A 35 relatively movable and dissimilar guide shoe 23 is carried by guide shoe 22 and is urged outwardly away from guide shoe 22 by means of springs 24 interposed between these guide shoes. Overhanging end portions 25 formed on the guide 40 shoe 23 are adapted to ride in suitable receiving and supporting recesses 26 provided in the guide shoe 21. In use, the expansive action of springs 24 urges the guide shoes into engagement with the guide slot in the threshold plate.

It will be apparent that the novel guides of 45 the present invention may be made of wood, metal or other materials, if desired, although the novel self lubricating composition of this invention is preferable. These guides may be used for various purposes other than for guiding sliding 50 doors. They may be used wherever one member slides with respect to another and a guide is used for guiding the relative motion. Thus, these guides may be used in double-hung windows, for example, such as in metal windows for guiding the sash.

As many changes could be made in the above 55 construction and many apparently widely different embodiments of this invention could be made without departing from the scope thereof, it is intended that all matter contained in the above description or shown in the accompanying drawings shall be interpreted as illustrative and not in a limiting sense.

What is claimed is:—

1. In a guide for attachment to a sliding door comprising, a guide shoe member having a recessed intermediate portion and end portions arranged to be secured to the door, a cooperative guide shoe member disposed within said recessed intermediate portion and movable outwardly thereof, and spring means positioned within said recessed intermediate portion and interposed between said guide shoe members for urging the same with equal pressures away from each other for cooperating with a guide groove. 5

2. In a guide for attachment to a sliding door comprising, a guide shoe having a narrow body portion and enlarged head portions formed integral with the ends of said body portion, said head 15 portions being apertured for attaching the same to a door and having supporting recesses formed therein, a cooperative guide shoe having projecting end portions extending into said supporting recesses, whereby said cooperative guide shoe is 20 supported upon said first mentioned guide shoe, and spring means interposed between said guide shoes for urging the same with mutually balanced pressures away from each other.

3. In an elevator door assembly in which the 25 door is supported from the top for horizontal sliding movement and in which means are arranged in the sill beneath the door to provide a channel extending in the direction of movement of the door, a guide for operation in said 30 channel to guide the door at the bottom, said guide comprising a non-metallic guide shoe member, a supporting member for said guide shoe member secured to the bottom of the door and extending downwardly into said channel, said 35 supporting member being of a width less than that of said channel, and resilient means for moving said guide shoe member outwardly into engagement with one side of said channel.

4. In an elevator door assembly in which the 40 door is supported from the top for horizontal sliding movement and in which means are arranged in the sill beneath the door to provide a channel extending in the direction of movement of the door, a guide for operation in said channel 45 to guide the door at the bottom, said guide comprising a supporting member secured to the bottom of the door and extending downwardly into said channel, said supporting member being of a width less than that of said channel, a non- 50 metallic guide shoe means associated with said supporting member, and resilient means for moving said guide shoe means to engage said sill within said channel.

RALPH L. HENRY. 55
